UNITED STATES PATENT OFFICE.

CHARLES SPAHR, SR., OF ALGIERS, LOUISIANA.

CONTINUOUS RAILWAY CROSSING.

Application filed August 10, 1927. Serial No. 211,997.

This invention relates generally to improvements in railway crossings but specifically has to do with a device adapted for bridging the gap between the main rail and 5 guard rail of a crossing.

The primary object of the invention resides in the provision of a device of the above-mentioned character which is adapted for removable connection between the main 10 and guard rails of a crossing.

Another object of the invention is to provide a filler member, resiliently carried by a supporting member, and adapted to bridge the gap between the main and guard rail top 15 flanges.

Still another object is to provide means for conveniently removing or replacing said filler member in the event of injury thereto.

With these general objects in view, together with others which will appear as the description proceeds, the invention resides in the novel formation, combination, and arrangement of parts, all as will be described more fully hereinafter, illustrated in the 20 drawings, and particularly pointed out in the claims.

In said drawings:

Figure 1 is a diagrammatic view of a portion of a railway crossing illustrating in plan the attachment of my device thereto.

Fig. 2 is a transverse sectional view taken substantially through the filler member of Fig. 1 to illustrate the mounting of body portion of the device between the main and 35 guard rails.

Fig. 3 is an enlarged side elevation of the device; and

Fig. 4 is a plan view of the same.

In practically all railway crossings, at 40 junctions or the like, it is and has been the practice to join the intersecting rails so that a gap is provided therebetween for the passage of the flange of a wheel, and in view of the presence of this gap considerable injury 45 is likely to occur to the rails due to the contact therewith of a wheel in its passage therover.

In order to cure this defect, I propose to provide means for bridging said gap in order 50 to provide a continuous surface for the passage of the wheel and at the same time mount said means at an intersecting point so that the same may be deflected out of the path of the flange of a wheel during its passage through the intersection.

Referring now to Figure 1 of the draw-

ings, let 5 denote the main rail of an intersection and 6 the usual guard rail, their disposition being such as to provide continuous 60 passages 7 and 8 between the same and arranged at right angles with each other. Thus a wheel travelling in the direction of the arrow will contact the main rail 5 and ride over the gap formed in passage 8, while its flange will ride in the passage 7. Similarly a wheel traveling at right angles to the first-mentioned wheel will bridge the gap in the passage 7, its flange riding in the passage 8. These conditions being true for each 65 intersection, and hence Figure 1 may be considered as a typical example thereof.

The device forming the subject-matter of this application comprises a body portion 9 having upwardly directed side members 10 and 11, said body portion being of suitable 75 size and formed to snugly fit between the webs of the main and guard rails 5 and 6 and also between the top and bottom flanges of said rails, as clearly shown in Fig. 2.

In order to accommodate the wheels of 80 the train moving in different directions, two of my devices will be installed at each intersection, and as shown in Fig. 1 the bases of the body portions are forwardly extended, as indicated at 12, and then bevelled, as at 13, to form a snug fit. It will 85 of course, be understood that the side members 10 and 11 preferably terminate flush with the side edges of the top flanges of the rails.

It is manifest that a wheel traveling in 90 the direction of the arrow in Fig. 1 must ride over the gap 8 which I have bridged with a member 14. However, before said wheel reaches said member, a similar member 15 mounted in the passage 7 will be contacted by the flange of said wheel and hence 95 it becomes necessary to provide means for the temporary removal of said member 15. To this end each of said side members 10 and 11 are provided with horizontally aligned 100 apertures 16 and 17 for the reception of trunnions 18 and 19 carried by each of said members 14 and 15 and in view of this arrangement 105 said members may be rotated in either direction and in either case their contact by the flange of a wheel results in their removal from the path thereof. In order 110 to restore each of said members 14 and 15 to their original positions, I have provided resilient means in the form of a spring 20, one end thereof being secured to the abut-

ment 21 of the body portion 9, while the other end is preferably attached to a link 22 joined to the respective members 14 and 15.

5 In mounting the devices between the main and guard rails it is only necessary to insert the body portion just beyond the point where the guard rail terminates, whereupon they are slid to the intersection until the beveled portions 13 abut. Bolts 23 and 24, or other suitable fastening means may then be passed through the apertures 25 and 26 in said body portions of the devices to securely fasten the same in position.

10 15 When the devices are to be removed it is only necessary to remove said bolts and in the event a repair or replacement is to be made therein the movable parts thereof may be readily disassembled by withdrawing the screws 27 and 28 thus freeing the side member 11 and permitting the removal of the members 14 and 15. The point of separation between said body portion 9 and the side member 11 is indicated at 29 in Fig. 3 20 and by preference a mortise joint 30 is provided to assure a positive fitting between the parts and to assure a re-alignment of the apertures 16 and 17.

25 From the foregoing it is apparent that 30 one of the members 14 and 15 always bridges the gap between the main and guard rails and that its companion is adapted to be tilted or rotated by the flange of a wheel depending of course upon the direction in 35 which said wheel is travelling.

While the present is a disclosure of the

preferred embodiment of the invention, it is to be understood that the invention is not limited thereto, as various changes in the minor details of construction, proportion 40 and arrangement of parts may be resorted to without departing from the spirit of the invention as defined in the appended claims.

I claim:

1. A device of the character described 45 comprising a body portion adapted to be removably inserted between the main and guard rails of a railway crossing and embodying upwardly directed side members and a filler member rotatably mounted between 50 and extending above said side members and adapted to bridge the gap between the top flanges of said main and guard rails, one of said side members being removably connected to said body portion.

2. A device of the character described comprising a body portion adapted to be removably inserted between the main and guard rails of a railway crossing and embodying upwardly directed side members, a 55 filler member rotatably mounted between and extending above said side members and adapted to bridge the gap between the top flanges of said main and guard rails, one of said side members being removably connected to said body portion and yieldable 60 means connected to said filler member for restoring the same to its normal position after depression by the flange of a wheel.

In testimony whereof I affix my signature.

CHAS. SPAHR, Sr.
